J. S. SULLIVAN

TOWEL CABINET

Filed July 17, 1925

Patented Mar. 30, 1926.

1,578,614

UNITED STATES PATENT OFFICE.

JAMES S. SULLIVAN, OF BIRMINGHAM, ALABAMA.

TOWEL CABINET.

Application filed July 17, 1925. Serial No. 44,140.

To all whom it may concern:

Be it known that I, JAMES S. SULLIVAN, a citizen of the United States of America, residing at Birmingham, in the county of Jefferson and State of Alabama, have invented certain new and useful Improvements in Towel Cabinets, of which the following is a specification.

My invention relates to an improvement in 10 towel cabinets suitable for use with both individual and rolled towels, and which is characterized by the fact that when the individual towels are employed the standard upon which they are mounted can be unlocked and removed with the greatest possible 15 expedition to the end that the number of cabinets which may be served by an attendant within a given time limit may be very materially increased over the present 20 practice.

In cabinets as now constructed, the attendant finds difficulty and encounters delay in getting his control key inserted in the key hole for unlocking the post or 25 standard for the individual towels.

Inasmuch as cabinets of this character as a general rule are furnished by the towel supply concern and as it is frequently necessary to utilize different kinds of towels or 30 to change the cabinet from a customer desiring individual towels to one desiring a rolled towel, or to one using both, I have conceived that it will be of material advantage to such towel supply concerns if the cabinet 35 without detracting from its appearance is adapted to use both types of towels, and in addition thereto to furnish ample space in which brushes, combs and the like toilet articles, or extra rolled towels can be placed.

40 My invention will be best understood by reference to the accompanying drawings in which my invention is illustrated in its preferred embodiment only, and in which:—

45 Fig. 1 is a vertical cross-sectional view taken on the line 2—2, but showing the cabinet supplied with individual towels.

Fig. 2 is a front elevation of the cabinet supplied with rolled towels.

50 Fig. 3 is a sectional detail view through the hinged edge portion of the upper shelf showing the lock casing in position.

Similar reference numerals refer to similar parts throughout the drawings.

55 In the embodiment of my invention illustrated, I show a cabinet comprising short front legs 1 and 2 connected respectively by

top and bottom side bars 3 and 4 with high back legs 5 and 6. The front legs are cross connected top and bottom by an upper bar 7 and a lower bar 8, and the rear legs are 60 cross braced by a lower bar 9, an upper bar 10, and two spaced top bars 11 and 12. Vertical slats 13 connect the upper and lower cross bars, and with bottom slats 14, connecting the bottom bars 4, form an open receptacle at the base of the cabinet for the reception of soiled towels. Between the top bars 11 and 12 I mount in a suitable frame 65 a mirror 15 and I attach to the legs 5 and 6 immediately below the mirror a backboard 16 having forwardly extending side boards 17 and 18. I connect to the boards 16, 17 and 18 a bottom shelf 19, having a short upright front board 20. Suitably spaced above the shelf 19 is a shelf 21 having a front 70 strip 22 connected thereto by upwardly folding hinges 23. The front edge of the strip 22 stands flush with the front board 20 on the shelf below. I mount in the center of this strip 22 near its free edge a lock casing 75 80 which is adapted to receive the notched base of a metallic post or standard 25 and to snap lock the post in upright position on the strip. The lock casing 24 has a key hole in its bottom face and the post, as 85 seen in Fig. 1, is so disposed that when free of towels it can fold over with the strip 22 to the dotted line position, Fig. 1, thereby exposing the key hole in the casing so that the key can be readily inserted to unlock 90 and detach the post. The post has an eye at its upper end which has connected thereto a chain or other towel guide or carrier 26 adapted to drop down into the soiled towel 95 compartment. The chain shown has secured at its lower end a weighted ball 27 larger than the grommets in the individual towels 28 so that the latter cannot be detached from the chain until the post is unlocked and removed from the lock casing 24. 100 The arrangement of the shelves 19 and 21 is such as to afford between them a convenient compartment 29 in which toilet articles 30 can be placed when the cabinet is used for individual towels, as shown in Fig. 1.

When, however, it is desired to use the cabinet for rolled towels 31, the latter are mounted on a spring bar 32 attached to the underside of the bottom 19, the free end of the bar being adapted to catch in a hanger 33 from which it can be readily disengaged for the removal and replacement of the tow-

els. When rolled towels are used, the toilet articles can be placed upon the shelf 21 and the rolled towels stored in the compartment 29, the post 25 being, if desired, unlocked and with its chain 26 removed from the cabinet. In this manner the cabinet can be used with different kinds of towels and it will thus constitute a universal cabinet for the commercial towel service.

10 In use the individual towels 28 when used are packed in quantity with a guide through their grommets. They are placed on the upper shelf with the grommets overhanging and as the guide is removed the post 25 is 15 passed down through the grommets and then is inserted and locked in the casing 24 with its end dropped down into the soiled towel compartment. As the towels are used they are lifted up over the post and when released fall down by the chain into the soiled 20 towel compartment. When used for rolled towels, the latter are deposited in the compartment 29 and are hung one at a time on the hanger 32 and all desired toilet articles 25 are placed on top of the shelf 21.

Though I have described with great particularity the details of the embodiment of the invention herein shown, it is not to be construed that I am limited thereto, as 30 changes in arrangement and substitution of equivalents may be made by those skilled in the art without departing from the invention as defined in the appended claims.

Having thus described my invention, what I claim as new and desire to secure by Letters Patent, is:—

1. A towel cabinet of the character described, comprising a stand having a shelf with its forward edge portion hinged to fold over upwardly, and a lock means adapted to 40 receive an individual towel post and carrier mounted in the forward hinged edge portion of the shelf, said lock means having a bottom key hole adapted to be exposed when the hinged shelf edge and post are folded 45 rearwardly.

2. A towel cabinet as set forth in claim 1, in which the towel post extends upwardly at such an angle and is so disposed that it will lie upon the rear portion of the shelf when 50 the hinged portion of the shelf is folded upwardly.

3. A towel cabinet of the character described, comprising a stand having spaced shelves forming between them a storage 55 compartment, the upper shelf having its forward edge portion hinged to fold upwardly, and a lock means adapted to receive an individual towel post and carrier mounted in the outer hinged edge portion of the upper shelf, 60 the lock means having a bottom key hole adapted to be exposed when the hinged shelf edge and post are folded rearwardly.

In testimony whereof I affix my signature.

JAMES S. SULLIVAN.
